Primary Examiner — Katrina N Gonzalez(74) *Attorney, Agent, or Firm* — Vidas, Arrett & Steinkraus PA; Richard A. Arrett; Edwin E. Voigt, II(57) **CLAIM**

The ornamental design for a chew guard, as shown and described.

DESCRIPTION

FIG. 1 is a front view of a chew guard, showing my new design in an environmental view.

FIG. 2 is a perspective view of the chew guard, but shown separately for clarity of illustration.

FIG. 3 is a top plan view thereof;

FIG. 4 is a front view thereof;

FIG. 5 is a left side view thereof;

FIG. 6 is a rear view thereof;

FIG. 7 is a right side view thereof; and,

FIG. 8 is a bottom plan view thereof.

The horse stall gate in FIG. 1 is not intended to be part of the design and will be shown in silhouette when formal patent drawings are filed.
